DESIGN FOR A TIE CLASP

Benjamin Glastal, New York, N. Y.

Application March 20, 1945, Serial No. 118,594

Term of patent 14 years

(Cl. D17—10)

To all whom it may concern:

Be it known that I, Benjamin Glastal, a citizen of the United States, residing in the city of New York, county of Bronx, and State of New York, have invented a new, original, and ornamental Design for a Tie Clasp, of which the following is a specification, reference being had to the accompanying drawing, forming a part thereof.

Figure 1 is a front view of a tie clasp, showing my design.

Figure 2 is a side view of the clasp.

Figure 3 is a rear view thereof.

Figure 4 is an end view of the clasp.

I claim:

The ornamental design for a tie clasp, as shown.

BENJAMIN GLASTAL.
